UNITED STATES PATENT OFFICE

117,716

DESIGN FOR AN ASHTRAY

Edward B. Herman, Minneapolis, Minn.

Application September 2, 1939, Serial No. 87,011

Term of patent 14 years

To all whom it may concern:

Be it known that I, Edward B. Herman, a citizen of the United States, residing at 305 East 15th Street, Minneapolis, in the county of Hennepin and State of Minnesota, have invented a new, original, and ornamental Design for an Ashtray, of which the following is a specification, reference being had to the accompanying drawing, forming part thereof.

Fig. 1 is a top plan view of an ashtray showing my new design;

Fig. 2 is a view in side elevation of said tray; Fig. 3 is a vertical section taken on line 3—3 of Fig. 1 as indicated by the arrows; and Fig. 4 is a bottom plan view of said tray.

I claim:

The ornamental design for an ashtray, as shown.

EDWARD B. HERMAN.
